UNITED STATES PATENT OFFICE.

JOSEPH P. ONERBACKER, OF LOUISVILLE, KENTUCKY.

DESIGN FOR A STOVE-DOOR.

SPECIFICATION forming part of Design No. 35,582, dated January 14, 1902.

Application filed December 18, 1901. Serial No. 86,448. Term of patent 14 years.

To all whom it may concern:

Be it known that I, JOSEPH P. ONERBACKER, a citizen of the United States, residing at Louisville, in the county of Jefferson and State of Kentucky, have invented and produced a new and original Design for a Stove-Door; and I do hereby declare the following to be a full, clear, and exact description of the same, reference being had to the accompanying drawing, forming a part thereof.

The drawing represents a perspective view of my design for a stove-door.

My design consists in a door A, illustrated in the accompanying drawing, having straight parallel top and bottom edges *a* and *b*, joined at one side by a perpendicular edge *c*, the top edge being shorter than the lower edge and the side opposite the perpendicular side having an inwardly-extending compound-curved portion *d*. The whole door is swelled outward from the plane of its edges, and the central portion is ornamented by an embossed large double-ended foliated volute *e*, surrounded

by a scallop *f*. The corner adjacent to and below the compound-curved portion is further 25 ornamented by an embossed double-ended foliated volute *g*, having a fluted scroll *h* below the same. The other three corners of the door are ornamented by double-ended foliated volutes of reduced size, (indicated at *i i i*.) 30 Fluted scrolls *j* and *k* extend from the scallop *f* to the top and bottom edges of the door, respectively.

The edges of the door are outlined by a foliated border *l*.

What I claim, and desire to secure by Letters Patent, is—

The design for a stove-door, substantially as herein shown and described.

In testimony whereof I affix my signature 40 in presence of two witnesses.

JOSEPH P. ONERBACKER.

It is hereby certified that the name of the patentee in Letters Patent No. 35,582, granted January 14, 1902, for a Design for a "Stove-Door," was erroneously printed "Onerbacker," whereas said name should have been printed *Ouerbacker*; and that the said Letters Patent should be read with this correction therein that the same may conform to the record of the case in the Patent Office.

Signed, countersigned, and sealed this 4th day of February, A. D., 1902.

F. L. CAMPBELL,
Assistant Secretary of the Interior.
